METHOD OF AND APPARATUS FOR STEAMING AND REFINISHING CLOTH

Filed April 13, 1929 .

UNITED STATES PATENT OFFICE

ISREAL COHEN, OF PHILADELPHIA, PENNSYLVANIA

METHOD OF AND APPARATUS FOR STEAMING AND REFINISHING CLOTH

Application filed April 13, 1929. Serial No. 354,846.

My invention relates to a new and useful method of and apparatus for steaming and refinishing cloth incident to the shrinking thereof, before use or consumption.

5 It has heretofore been the practice to employ a manually or electrically rotated steam cylinder over which the cloth to be steamed and refined was adapted to pass and around which said cloth was simultaneously 10 wound into a roll of a thickness commensurate with the length of the cloth being treated, there being an upper idle press roll co-acting with said steam cylinder to supply the necessary pressure for refinishing or smoothing out the cloth.

This practice was disadvantageous in that the innermost layers of the cloth being treated, that is, the layers of cloth contacting with or immediately adjacent the superheated 20 steam cylinder were scorched, while the outer layers were far removed from the steam cylinder by the intervening layers of the cloth wound around the steam cylinder.

A further disadvantage lay in the fact 25 that when the steamed and refined roll of cloth is wound around the steam cylinder, it is necessary to remove the latter entirely and to install a fresh steam cylinder for the treatment of another roll of cloth. This not only 30 involved the constant connection and disconnection of the steam cylinder to the steam supply pipes, but also necessitated the maintenance of a large number of steam cylinders, thus greatly increasing the capital investment 35 in addition to decreasing the efficiency.

It is the object of my invention to obviate these disadvantages and to provide means whereby the cloth being steamed and refined is uniformly and sufficiently treated 40 throughout its entire length, without scorching some portions of said cloth and insufficiently steaming and refinishing other portions thereof.

A further object of my invention is to provide novel means wherein a single steam cylinder 45 may be employed for the treatment of any number of rolls of cloth successively without the necessity of connecting, disconnecting and re-connecting the steam cylinder after the refinishing and steaming of each roll

of cloth, thus effecting considerable economy in the cost of equipment and the cost of operation.

To the above ends my invention consists of an upright frame, an apertured steam cylinder 55 rotatably mounted thereon, an idler press roll superimposed upon said steam cylinder and coacting therewith, the axis of said press roll being out of vertical alignment with that of said steam cylinder, and a platform in advance of and below said steam cylinder, upon which the cloth being treated is adapted to travel as it is fed or propelled to said steam cylinder.

My invention further consists in the novel 60 method of winding the cloth after it is steamed and refined, all as hereinafter described and claimed.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein 70 shown and described.

In the accompanying drawings:—

Figure 1, represents a front elevation of a cloth steaming and refinishing device embodying my invention.

Figure 2, represents on an enlarged scale, 80 a section on line 2—2 of Figure 1, illustrating the manner of carrying out my novel method by means of my novel apparatus.

Referring to the drawings in which like 85 reference characters indicate like parts, 1 designates a cloth steaming, refinishing and rolling device embodying my invention, comprising the uprights 2 and the transverse, horizontal brace and table or platform member 3. 4 designates a steam cylinder perforated at 5 and supplied with live steam through the feed pipe 7, the valve 8 and the suitably packed coupling 9, said steam cylinder having at the other end thereof a shaft 95 carrying the sprocket wheel 10, over which 100

passes the sprocket chain 11, which in turn is actuated by a suitable source of power (not shown) it being understood that the actuation or rotation of the steam cylinder can be effected in any other desired or suitable manner.

The steam cylinder 4 is covered with one or more layers of canvas, duck or other fabric 12 to insulate the cloth 13 from immediate contact with the outer metallic surface of the steam cylinder 4, to prevent scorching of said cloth, and to disperse or diffuse the jets of steam emanating from the ports or perforations 5 of said steam cylinder to effect uniform distribution of the steam to all parts of the cloth 13. The parts heretofore described are conventional, and as stated, it has heretofore been the practice to wind the cloth 13 continuously over the steam cylinder 4 in the direction of the arrows 14 and 15 so that the innermost layers of the cloth 13, that is, those layers of the cloth 13 contacting with or immediately adjacent the canvas layers 12, were superheated and scorched while the outermost layers of the roll of cloth formed on said steam cylinder were necessarily underheated and not sufficiently steamed.

By my invention, I employ an idle press roll 16 loosely superimposed upon the steam cylinder 4, and suitably covered with layers of canvas or duck 18. The press roll 16 has the journals 19, the outer ends of which carry the nuts 20, which engage the outer surfaces of the uprights 2 to prevent the longitudinal displacement of said press roll as will be understood from Figure 1. The journals 19 of the press roll 16 are positioned between the uprights 2 and the vertical plane of the axis of the steam cylinder 4 (see Figure 2) so that said press roll or idler gravitates towards said uprights and no extraneous retaining means are necessary for retaining said press roll in operative relation upon said steam cylinder. With this novel mechanical arrangement, I carry out my novel method of steaming and refinishing the cloth 13 by feeding the cloth 13 in the direction of the arrow 14 over the steam cylinder 4 in the direction of the arrow 15, and reversing the winding of the cloth 13 over the idle press roll 16 in the direction of the arrow 21. By this arrangement I assure the uniform and sufficient steaming of every portion of the cloth 13, since it passes in but a single thickness over the steam cylinder 4, and I guard against damaging any particular portion of the cloth by protracted steaming or excessive temperature as invariably occurs when prior art constructions are employed, wherein the roll of cloth 13 is wound continuously around the steam cylinder, thus bringing the innermost layers of cloth into immediate contact with the superheated steam cylinder, as hereinabove explained.

Furthermore, by winding the cloth 13

around the press roll 16 instead of around the steam cylinder 4, it is merely necessary to remove the loosely mounted press roll 16 carrying the roll of cloth which has been steamed and refinished, thus obviating the necessity of disconnecting and reconnecting the steam cylinder 4, which would be necessary were the roll of cloth 13 wound around said steam cylinder. By winding the cloth over or around the press roll 16, which is but a solid roll of any desired size, and hence not as expensive as the steam cylinder 4, I reduce the number of steam cylinders required and increase the number of press rolls 16 needed, thereby effecting a saving in the initial cost of the equipment necessary.

I further increase the efficiency of the device by obviating the necessity of repeatedly disconnecting the heated steam cylinder after the treatment of each roll of cloth, thus economizing in the heat energy consumed, as well as in the labor and time involved.

By the offset position of the press roll 16, with respect to the steam cylinder 4, I am enabled to retain the former in position with respect to the latter without the aid of any extraneous fastening or securing devices, the weight of said press roll being sufficient to retain the latter in position upon the steam cylinder at all times, as will be best understood from Figure 2.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I claim as new and desire to secure by Letters Patent, is:

1. In a device of the character stated, an upright frame, a perforated cylinder rotatably carried by said frame, means for rotating said cylinder, an idle press roll positioned upon and rotatable with said cylinder, the longitudinal axis of said press roll being disposed between vertical planes passing through said upright frame and through the longitudinal axis of said cylinder, and end journals for said press roll adapted to bear against the upper ends of said frame to prevent horizontal displacement of said press roll.

2. In a cloth steaming and refinishing device, an upright frame, a perforated cylinder rotatably carried by said frame below the upper ends thereof, means for rotating said cylinder, a steam supply therefor, an idle press roll positioned upon and rotatable with said cylinder, the longitudinal axis of said press roll being disposed between vertical planes passing through said upright frame

and through the longitudinal axis of said cylinder, and journals for said press roll adapted to engage the juxtaposed faces of said upright frame to prevent horizontal displacement of said press roll, and adjustment nuts 5 carried by said end journals adapted to engage the outer faces of said upright frame to prevent longitudinal displacement of said press roll.

3. In a device of the character stated, means 10 for supporting and rotating a perforated steam cylinder, an upper idle press roll positioned upon and rotatable with said cylinder, the longitudinal axis of said press roll being out of vertical alignment with the axis 15 of said cylinder, journals for said press roll, and abutments for said journals.
